UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

LOOP-KEY.

SPECIFICATION forming part of Letters Patent No. 433,046, dated July 29, 1890.

Application filed March 13, 1885. Serial No. 158,762. (No model.)

To all whom it may concern:

Be it known that I, CHARLES E. SCRIBNER, a citizen of the United States, residing at Chicago, in the county of Cook and State of Illinois, have invented a certain new and useful Improvement in Loop-Keys, (Case 92), of which the following is a full, clear, concise, and exact description, reference being had to the accompanying drawings, forming a part of this specification.

My loop-key is designed especially for use in connection with the switch-boards of telephone-exchanges for making the connections and disconnections between the operator's outfit and the telephone-lines.

In the drawings, Figure 1 is a side elevation of my loop-key or switch mounted upon its support and ready for use. Fig. 2 is a view thereof, partially in section, showing the conducting-plunger forced down so as to form contact with one of the contact-springs and force said springs apart so as to separate them from the contact-points upon which they ordinarily rest. Fig. 3 is a diagram illustrative of the circuits of the telephone and transmitter in connection with the cords and clearing-out shutter, showing the clearing-out shutter in circuit.

Like parts are indicated by similar letters of reference in the different figures.

The base or support *a*, upon which my key is mounted, may be the table or shelf at the front of the switch-board. The springs or contact-pieces *b* and *c* are mounted, as shown, and insulated from each other, and are so adjusted as to normally rest in contact with insulated contact-points *d* and *e*, respectively.

The contact-plunger *f* is normally held away from the free ends of the contact-springs by means of the coil-spring *g*. This coil-spring is placed about the stem of the plunger below the collar *h* within the metallic socket *i*, good electrical connection being constantly maintained between the plunger and socket by means of the coil-spring.

The contact-spring *c* is provided with insulation *k* at its free end. The spring *b* at its free end is bent, as shown, toward the free end of spring *c*.

The plunger is provided with the conical

head *l*, which, when forced down, as shown in Fig. 2, serves as a wedge, forcing said contact-springs apart, disconnecting said springs from contact-points *d e*, while a new connection is formed between the plunger and spring *b*. I preferably use a cam-lever *m*, as shown, to operate the plunger. By throwing the cam-lever back, as shown in Fig. 2, the plunger will be forced down and the springs separated, as before described. On throwing the cam-lever forward the plunger will be lifted by the coiled spring and the free ends of the contact-springs will move toward each other, spring *b* closing upon point *d* and spring *c* upon point *e*, as shown in Fig. 1.

The contact-springs, as well as the contact-points *d e*, as shown in the drawings, are mounted on a block *m* of insulating material, preferably hard rubber. The block *m* may be made of any desired length. I preferably make it long enough to accommodate several keys. As the plunger is fitted to its socket, it moves up and down without side motion, and the contact-keys are lifted simultaneously from or closed simultaneously upon contact-points *d e*. As the head of the plunger touches the free end of spring *b*, electrical connection is formed between said spring and the socket. The plunger, as it is forced further down, lifts the springs from contacts *d e*, as before described. It will thus be seen that a continuity of contact is maintained between the plunger and spring *b* until the springs have closed upon contact-points *d e*.

As used in telephone-exchanges, each of the contact-springs is permanently connected with a different flexible conducting-cord, said cords being provided with ordinary terminal plugs for insertion in the spring-jacks upon the switch-board.

The contact-points *d e* are connected together by a wire, in the circuit of which is placed the operator's outfit, consisting of a transmitter and receiver.

The plunger, through the medium of the socket, is permanently connected by a wire with spring *c*, and in the circuit of said wire is included a clearing-out annunciator.

In my application (Case 93) executed March 28, 1885, and filed April 6, 1885, Serial No. 100

161,322, I have shown a switch or test key in some respects similar to the one herein described.

I claim—

- 5 1. The combination, with insulated contact-springs forming the terminals of a loop-circuit, and normally resting upon insulated contact-points, of the plunger placed between said springs and serving as a wedge, when de-
10 pressed, to separate said springs and form electrical connection with one of said springs during all the time said spring is lifted from its contact-point.
- 15 2. The combination, with converging contact-springs mounted upon opposite sides of a block of insulating material and forming the terminals of a loop-circuit, of insulated contact-points *d* and *e*, against which, respectively, said springs normally rest, and a plun-
20 ger placed between said springs and provided with a conical head which serves as a wedge

to separate the said springs and lift them from contact-points *d* *e*, substantially as and for the purpose specified.

3. The combination, with the contact-
25 springs mounted upon the block of insulating material, of the telephone contact-points, the plunger provided with the beveled head, the coiled spring which holds the plunger away from said contact-springs, and the cam-lever, 30 whereby said plunger may be forced down against the free ends of said contact-springs to separate said springs from said contact-points, thereby lifting said contact-springs from the telephone contact-points, respect- 35 ively, substantially as described.

In witness whereof I hereunto subscribe my name this 17th day of February, A. D. 1885.

CHARLES E. SCRIBNER.
